UNITED STATES PATENT OFFICE.

FREDERICK BENJIMAN MASLEN, OF MOBERLY, MISSOURI.

HANGER FOR SLIDING SASHES.

1,088,434.

Specification of Letters Patent.

Patented Feb. 24, 1914.

Application filed July 26, 1913. Serial No. 781,351.

To all whom it may concern:

Be it known that I, FREDERICK B. MASLEN, a citizen of the United States, and a resident of Moberly, in the county of Randolph and State of Missouri, have invented a new and useful Improvement in Hangers for Sliding Sashes, of which the following is a specification.

My invention has for its object to provide a hinge for connecting the said frames and so arranged as to permit the complete detachment of the frames or the detachment at either side of the said frames to permit the said frames to swing with respect to each other.

In the drawings:—Figure 1 is a front view of a window casement and sash connected by the improved hinge, and Figs. 2 and 3 are sections on the line 2—2 and 20 3—3, respectively, of Fig. 1.

The present embodiment of the invention is shown in connection with a sash, consisting of an outer frame 1, arranged to slide in the casement in the ordinary manner, and 25 an inner frame 2 connected with the outer frame, and normally forming a part thereof. The frames are connected by four of the improved hinges, the said hinges being arranged at the corners of the frame, and 30 each hinge consists of two leaves, one connected to the outer frame and one connected to the inner frame.

Each of the leaves is of angular shape, the leaf connected with the outer frame consisting of portions 3 and 3^a, while the leaf connected with the inner frame consists of portions 4 and 4^a, the said portions of each leaf being at a right angle with respect to each other. Each of the portions 3 and 3^a 40 of the first-named leaf 4 and 4^a of the second-named leaf, is provided with openings for receiving screws 5, to connect them to the frames.

The leaf 3—3^a is arranged with its inner edge flush with the inner edge of the outer frame, and the leaf 4—4^a is arranged with its outer edge flush with the top and side edges of the inner frame, and both leaves are countersunk in the faces of the frames.

50 Near its upper end the portion 3 of the leaf

3—3^a is offset laterally, as shown at 6, in Fig. 2, the offset portion being connected to the body of the leaf by means of webs 7, integral with the offset portion and the body of the leaf, to form a recess or species 55 of casing, for receiving a hinge lug, to be presently described.

The portion 4 of each of the leaves 4—4^a is provided with a lug 8, for engaging the recess or casing of the adjacent leaf 3—3^a, 60 the said lug extending laterally from the inner face of the leaf, and also extending beyond the outer edge of the leaf. The lug 8 and the webs 7 of the recess or casing are provided with registering openings for 65 receiving a locking bolt 9, for hinging the leaves together. The said bolt is mounted to slide on the rear face of the portion 3 of the leaf 3—3^a, and the outer frame 1 is recessed to receive the said bolt and the casing or recess 6—7. The end of each bolt remote from the lug 8 is offset toward the inner face of the leaf as shown at 10 in Fig. 2, and a finger piece 11 is secured to the offset portion near the free end thereof, each 70 of the said finger pieces extending through a slot 12 in the bottom of a depression 13 in the outer face of the portion 3 of the leaf 3—3^a. The depression is formed by grooving the said portion of the leaf, and is of 75 sufficient depth to cause the outer end of the finger piece 11 to lie flush with the outer face of the hinge leaf. A plate spring 14 is secured at one end to the inner face of the portion 3 of the leaf 3—3^a, and the 80 free end of the said spring bears against the bolt 9, to prevent accidental disengagement of the said bolt. The spring presses the free end of the bolt against the side walls of the openings in the webs 7, and in the lug 8 to hold the said bolt in locking position 85 more especially at the upper end of the outer frame. At the lower end of the frame, the bolts are oppositely arranged, the free ends of each bolt being downward 90 instead of upward.

In use, either side of the frames may be released to permit the frames to swing with respect to each other and both sides of the inner frame may be released, if desired, for 100

removing the said frame to clean the same or for any other purposes.

I claim:—

5 A hinge consisting of leaves arranged in the same plane, one of the leaves having a casing extending laterally from the plane of the leaves, and the other leaf having a

lug adapted to fit within the casing, and releasable means for pivoting the lug to the casing.

FREDERICK BENJIMAN MASLEN.
